I. M. HESCHELES,
PARTITION STRUCTURE FOR BOXES.
APPLICATION FILED OCT. 4, 1920.

1,379,563.

Patented May 24, 1921.

UNITED STATES PATENT OFFICE.

ISIDORE M. HESCHELES, OF NEW YORK, N. Y.

PARTITION STRUCTURE FOR BOXES.

1,379,563.

Specification of Letters Patent. Patented May 24, 1921.

Application filed October 4, 1920. Serial No. 414,486.

To all whom it may concern:

- Be it known that I, ISIDORE M. HESCHELES, a citizen of the United States, residing at New York, in the county of New York and State of New York, have invented certain new and useful Improvements in Partition Structures for Boxes, of which the following is a specification, reference being had therein to the accompanying drawings.
- 10 This invention relates to a partition structure for boxes which is constructed so as to be removably carried within a box for horizontally dividing the box into a pair of compartments.
- 15 Another object of this invention is the production of a partition structure for boxes wherein the shelf is fixedly carried upon vertical walls whereby the shelf will be held spaced from the bottom and top of the box.
- 20 Another object of this invention is the production of a partition structure for boxes, wherein the walls are fixedly mounted upon the shelf for supporting the same,
- 25 projecting beyond a plurality of the side edges thereby permitting sufficient space for a person to grip the partition structure and lift the same from the box into its position.
- 30 Another object of this invention is the production of a partition structure for boxes, wherein the supporting walls are fixedly held upon the shelf by securing tacks passing through retaining bands, these
- 35 bands having bent ends projecting through the walls at distances from the ends of the walls, whereby the bent ends may be fixedly secured upon the free ends of the shelf while by passing through the walls
- 40 these bent ends will be efficiently reinforced.

With these and other objects in view, this invention consists of certain novel combinations, constructions and arrangements of parts as will be hereinafter fully described and claimed.

In the accompanying drawing:

Figure 1 is a top plan view of the partition structure for boxes showing the same positioned within a box.

Fig. 2 is a central longitudinal section through the partition structure showing the same within a box.

Fig. 3 is a detail perspective view of the partition structure.

Fig. 4 is a fragmentary sectional view

through one corner of the partition structure.

Fig. 5 is an enlarged fragmentary sectional view of a portion of the partition structure illustrating clearly the manner in which one of the bent ends passes through the supporting wall.

Fig. 6 is a plan view of one of the retaining bands.

Referring to the accompanying drawing by numerals, it will be seen that the partition structure is intended to be used in connection with an ordinary box 1 having the usual side walls 2.

The partition structure comprises a flat shelf 3 having one corner cut off as indicated at 4 although the remaining corners are square as indicated clearly in Fig. 1. The supporting walls 5 and 6 are positioned so as to fit upon one side edge and one end of the shelf 3 as shown in Figs. 1 and 3. These supporting walls 5 and 6 have their ends 7 projecting in suitable distances beyond the free side and end of the shelf 3 whereby when the partition structure is carried within a box sufficient space is provided for gripping the shelf 3 adjacent one of its edges when it is desired to lift the partition structure from the interior of the box. It will be noted, however, by referring to Fig. 1 that it is intended to have the partition structure of such a size as to cause the ends 7 of the supporting walls 5 and 6 to bear against the walls 2 of the box thereby holding the partition structure from wabbling or sliding about in the box.

In order to hold the supporting walls 5 and 6 in fixed engagement with the shelf 3, there are provided the retaining bands 8 as shown in Figs. 3 and 4. These retaining bands 8 comprise elongated bodies as shown in Fig. 6 and these bodies are bent adjacent their ends so as to provide each body with a bent end 9 extending at right angles to the body of the retaining band. The body and bent end of each retaining band is provided with apertures 10 through which the tacks 11 pass so as to be driven through the supporting walls and also pass into the shelf 3 for fixedly retaining the supporting walls and the retaining bands in engagement with the shelf. Since each of the supporting walls 5 and 6 has a projecting end 7 extending beyond the free side edge and free end of the shelf 3, each supporting wall is provided with a slot 12 extending therethrough

at points adjacent the free edge and free end of the shelf 3 as shown clearly in Figs. 3, 4 and 5. The bent ends 9 of the retaining bands 8 project through the slots 12 and 5 bear upon the free edge and free end of the shelf 3. A retaining tack 11' is passed through the opening formed in each bent end and is then driven into the shelf 3 of the partition structure for fixedly securing the 10 bent ends to the free edge and free end of the shelf 3. As a consequence, any tendency of the shelf to move away from the supporting walls is resisted by the retaining bands. Thus it will be seen that such urging upon 15 the shelf 3 will prevent the tacks driven through the supporting walls from tearing these walls or from becoming loose. This undesirable action is overcome by the retaining bands inasmuch as when for any 20 reason the shelf is urged away from the supporting walls, the bent ends 9 will prevent the action since they are fixedly mounted upon the shelf while the pulling action upon these bent ends under such conditions 25 would be taken up by the reinforcement of the projecting ends of the supporting walls 5 and 6, such reinforcement being occasioned by the bent ends projecting through the slots formed in the projecting ends of 30 the supporting walls. Furthermore, the mounting of the body portion of each band upon the tacks 11 will also assist in holding each band in a set position upon the supporting walls. It should further be noted 35 that the tacks 11 being driven far enough into the shelf 3 to provide a substantial even surface upon the outer surface of each retaining band, will cause the heads of the tacks to slightly bulge the retaining band 40 into the supporting walls 5 and 6 as shown at 13 whereby a binding action will be presented adjacent each tack for causing the retaining bands to assist in holding the side walls by the binding engagement above described in set positions upon the shelf 3 and 45 thus relieve considerable strain from the tacks 11 which might occasion the loosening of the tacks by slight bearing of the supporting walls when considerable weight is 50 placed upon the shelf 3. It is, of course, obvious that if so desired, tabs 14 may be

positioned upon the supporting walls and tacks 15 driven through these tabs, supporting walls and into the shelf for an additional support as shown clearly in Fig. 4. 55

From the foregoing description, it will be seen that a very simple and efficient partition structure for boxes has been constructed wherein the ends of the supporting walls are projected beyond the free edge and 60 free end of the shelf, thus causing the projecting ends to engage firmly the inner portions of the ordinary side walls of a box for holding the partition against shifting within the box. Furthermore, it will be seen that 65 sufficient space is provided for gripping the partition structure and lifting the same from a box while the extension of the bent ends of the retaining bands through the projecting ends of the supporting walls will reinforce these bent ends for assisting and holding the same when strain is brought to bear thereon in the retention of the shelf, while the inwardly bulged portions of the retaining band will constitute a binding action for 70 holding the bands upon the supporting walls without danger of the retaining tacks injuring the walls or becoming loose. 75

What I claim is:

As a new article of manufacture, in combination with a box, of a partition-structure therein comprising a vertical side-wall and a vertical end-wall of the same height as and fitting the inner faces of corresponding walls of said box to keep the partition-structure from accidental displacement, a horizontal shelf engaging the inner faces of and terminating short of the outer ends of said vertical walls, horizontal fastening means extending through said vertical walls and 80 fastened to the outer faces of said vertical walls and to the outer edges of said shelf within the outer marginal ends of said vertical walls, and said shelf provided with a cut-away corner for facilitating the gripping of the shelf when in the box for 85 quickly, manually removing the partition structure from the box. 90

In testimony whereof I hereunto affix my signature.

ISIDORE M. HESCHELES.
